MINING MACHINE

Frank A. Lindgren, Western Springs, Ill., assignor
to Goodman Manufacturing Company, Chi-
cago, Ill., a corporation of Illinois

Application December 5, 1932, Serial No. 645,648

25 Claims. (Cl. 262—30)

This invention relates to improvements in mining machines and more particularly to improvements in mining machines of the combination longwall and shortwall type particularly adapted for use in pitching seams of coal.

When cutting coal in pitching seams, either on the longwall or shortwall system, much difficulty is encountered in holding the machine up to the face while sumping the cutter bar into the coal and in preventing the machine from getting away from the operator during the cutting operation. Furthermore, it has heretofore been very difficult to sump the cutter bar of a longwall machine into the coal on a pitching seam by pivoting the cutter bar about the axis of its cutter chain sprocket due to the fact that the feed rope must be used for pivoting the cutter bar and some other means must be provided for holding the mining machine up to the face.

20 The device of my invention is so arranged as to eliminate these difficulties and has as one of its objects to provide a new and improved mining machine of the longwall type of a low compact arrangement which may also cut in the manner of a shortwall machine. Another object of my invention is to provide such a machine having a pair of feed drums independently driven from the mining machine motor in an improved manner and automatically held from rotation in a direction other than desired and controlled by suitable independent braking means when disconnected from the motor. Still another object of my invention is to provide auxiliary means operable independently of the feed drums at either a high positioning or a low feeding speed for pivoting the cutter bar for positioning said cutter bar or feeding it into the coal face.

Other objects of my invention will appear from time to time as the following specification proceeds.

My invention may be more clearly understood with reference to the accompanying drawings wherein:

45 Figure 1 is a perspective view of one embodiment of my invention;

Figure 2 is an enlarged plan view of the forward portion of the device shown in Figure 1, with parts broken away and in section to more clearly show the details thereof;

Figure 3 is a partial enlarged fragmentary longitudinal sectional view of the forward portion of the device shown in Figure 1;

55 Figure 4 is an enlarged plan view of the rearward portion of the device shown in Figure 1,

with parts broken away and in section to more clearly show the details thereof;

Figure 5 is an enlarged side elevation of the rearward portion of the device shown in Figure 1, with parts broken away and in section to more clearly show the details thereof; 5

Figure 6 is a sectional view taken substantially along line 6—6 of Figure 4;

Figure 7 is an enlarged side elevation of the rearward portion of the device shown in Figure 1, 10 with certain other parts broken away and in section than are broken away in Figure 5 to show certain other details of my invention;

Figure 8 is an enlarged detail sectional view of the locking and shifting arrangement for one 15 of the feed drums; and

Figure 9 is an enlarged detail view of the ratchet means for controlling one of the feed drums.

Like numerals refer to like parts throughout the various figures. 20

Referring now to the details shown in the drawings, the embodiment of my invention comprises a mining machine 10 of the type adapted to slidably move along the mine bottom on its own bottom during the cutting operation. Said mining 25 machine includes a motor 11, the height of which substantially determines the height of the machine, cutting mechanism disposed forwardly thereof and generally indicated by reference character 12 including a pivotally supported cutter bar 13 which may be locked in various positions with respect to said mining machine, which cutter bar has a cutter chain 14 movable thereabout in a closed orbital path, and feeding mechanism disposed rearwardly of said motor including feed drums 15, 15 disposed adjacent opposite sides of said mining machine, which drums have flexible feeding members 16, 16 wound thereon and are independently driven from the motor 11 in a manner which will hereinafter be more 40 fully described. 30

The cutter bar 13 is carried by a cutter bar support member 17 in a suitable manner, which cutter bar support member in turn has a bored portion which is journaled on a hub 18 depending 45 from a cutter frame member 19 secured to and extending forwardly of the motor 11. An annular bearing member 20 is formed integral with the cutter frame member 19 and has bearing engagement with a recessed portion formed in the upper 50 surface of the cutter bar support member 17 in a suitable manner. An annular ring 21 is secured to the cutter bar support member 17 adjacent its upper surface by means of suitable securing means in a well known manner and has bearing 55

engagement with the upper surface of the annular bearing member 20 for supporting the cutter bar 13 for pivotal movement about a vertical axis. Suitable means (not shown) are provided for 5 locking the cutter bar 13 in various positions of adjustment with respect to the longitudinal axis of the machine, which means are of an ordinary construction and are no portion of my present invention so are not herein shown or described in 10 detail. When the cutter bar 13 is locked so as to extend longitudinally of the machine, said machine may operate as a shortwall machine being fed into and across the coal face and controlled by means of the flexible feeding members 15 16, 16 in a usual manner, and when said cutter bar is free to be pivotally moved about its axis of pivotal connection to the cutter frame member 19 and locked so as to be positioned at right angles with respect to the machine, said machine 20 may operate as a longwall machine in a usual manner, being fed along the coal face by either one or both of the flexible feeding members 16 in a manner well known to those skilled in the art.

25 The cutter chain 14 is driven from the motor 11 about the cutter bar 13 by means of a suitable selective geared connection which comprises a pinion 22 secured to the forward end of a shaft 23 of the motor 11, which pinion meshes 30 with and drives a spur gear 24 keyed on a longitudinally extending shaft 25. The longitudinally extending shaft 25 is journaled in the cutter frame member 19 in a suitable manner and has a bevel pinion 27 freely mounted thereon, 35 and disposed rearwardly of the bearing support means for the forward end of said shaft.

The bevel pinion 27 is selectively connected with the longitudinally extending shaft 25 by means of a suitable clutch member 29 splined on 40 said shaft and having forwardly extending clutch jaws 30 formed integral therewith and engageable with suitable clutch jaws formed integral with said bevel pinion in a usual manner. A suitable clutch collar 31 is provided for shifting 45 the clutch member 29, which clutch collar in turn is operated by a clutch fork 32 and a suitable system of levers in a usual manner.

The bevel pinion 27 meshes with and has driving engagement with a bevel gear 33, which 50 bevel gear is keyed on the upper end of a vertical shaft 34. The bevel gear 33 is journaled on its hub in a suitable ball bearing supported in the hub 18 of the cutter frame member 19 and the vertical shaft 34 is journaled adjacent 55 the lower end of said hub in a suitable ball bearing in a usual manner. A cutter chain sprocket 35 is keyed on the lower end of the vertical shaft 34 and meshes with and drives the cutter chain 14 about the cutter bar 13.

60 Referring now in particular to the details of the feeding mechanism and several of the novel features of my invention, a spur pinion 36 is keyed on the rearward end of the motor shaft 23 and meshes with and drives a spur gear 37 65 keyed on the forward end of a longitudinally extending shaft 39. The longitudinally extending shaft 39 is journaled in a suitable bearing member 40 secured to a frame member 41 for the feed mechanism and has a worm 43, herein preferably shown as being formed integral therewith, intermediate its ends, which worm meshes with and drives a worm gear 44 keyed on a sleeve 45 freely mounted on a transversely extending shaft 46.

75 The transversely extending shaft 46 is pro-

vided with pinions 47, 47 adjacent its opposite ends, which pinions are in turn adapted to be selectively meshed with internal gears 48, 48 in a manner which will hereinafter be more fully described. The internal gears 48, 48 are in turn secured to the inner peripheries of inwardly extending flanges 49, 49 formed integral with the feed drums 15, 15 for driving said feed drums. The transversely extending shaft 46 is in turn adapted to be driven from the worm gear 44 at either a high or low frictionally controlled speed through a frictionally controlled plural speed planetary gear reduction device coaxial therewith and generally indicated by reference character 50.

15 The frictionally controlled planetary gear reduction device 50 is of an ordinary construction and includes a casing 51 freely mounted on the sleeve 45 and journaled on its hub in a suitable bearing member formed integral with the frame member 41. A sun gear 53 is formed integral with the sleeve 45 adjacent the inner end thereof within the casing 51 and meshes with and drives planetary pinions 54, 54 freely mounted on suitable shafts 55, 55 carried by a cage 56. 25 The planetary pinions 54, 54 mesh with an internal gear 57, which internal gear is secured to the inner periphery of the casing 51. Planetary pinions 59, 59 formed integral with the planetary pinions 54, 54 are of smaller diameter 30 than said pinions and mesh with and drive an internal gear 60 mounted for free rotation within the casing 51 and provided with a spider 61 within which are formed integral clutch jaws 62.

35 A suitable friction band, generally indicated by reference character 63, is adapted to engage the outer periphery of the casing 51 to hold said casing from rotatable movement or to allow said casing to slip therein for varying the speed of 40 the planetary gear reduction device 50 and for preventing overload on the parts therein and driven thereby in an obvious manner.

A suitable clutch member 64 is feathered on the transversely extending shaft 46 and is provided 45 with clutch jaws 65, which clutch jaws are adapted to mesh with the clutch jaws 62 formed integral with the spider 61 for driving said shaft at a low frictionally controlled speed, or suitable clutch jaws (not shown) formed integral with 50 the cage 56 for driving said shaft at a higher frictionally controlled speed in an obvious manner.

With reference now in particular to the novel means for selectively connecting the internal 55 gears 48 with the pinions 47 so that either of the feed drums 15 may be independently driven from the transversely extending shaft 46, said mechanism is the same for each drum, so the mechanism for one drum only will herein be described. 60

The feed drum 15 is freely mounted on a sleeve member 66 for rotation with respect thereto, which sleeve member is bored eccentrically of its center and carried by a sleeve 67 mounted on a transversely extending shaft 69 and journaled 65 within a bearing support 70 integral with and extending upwardly from the bottom of the frame member 41.

A groove 71 is formed in the outer end of the sleeve member 66 and extends thereacross. The 70 groove 71 is adapted to be engaged by arms 72 extending outwardly from the center of a member 73 carried within the sleeve 67 and keyed on the outer end of the shaft 69. Suitable means are provided for holding the member 73 and 75

sleeve 67 to the shaft 69 which herein comprises a nut and washer generally indicated by reference character 74, other means of a usual construction being provided for preventing lateral movement of the feed drum 15 with respect to the sleeve member 66 and preventing lateral movement of said sleeve member with respect to said first mentioned sleeve.

A lever arm 75 is keyed on the inner end of the shaft 69 and extends upwardly therefrom and is provided with a bifurcated upper end in which is carried a shaft 77 journaled at its ends in the prongs of said bifurcated upper end of said lever arm. Another parallel arm 79 is spaced 15 rearwardly from the lever arm 75 and carried in the frame member 41 for pivotal movement about an axis in alignment with the axis of pivotal movement of said lever arm. The parallel arm 79 is likewise provided with a bifurcated upper 20 end in which is carried a shaft 80.

The shafts 77 and 80 are transversely bored intermediate their ends, and the surfaces of said shafts adjacent the ends of said bores and between the prongs of said bifurcated portions are flattened. The bores of the shafts 77 and 80 are adapted to be aligned and receive a rod 81 passing therethrough so movement of said rod in one direction or another will move the lever arm 75 and parallel arm 79 in parallel relation with 25 respect to each other.

Suitable collars 82, 82, having tongues extending inwardly therefrom, are disposed adjacent opposite ends of the bifurcated portion of the lever arm 75 and their tongues extend within said bifurcated portion and abut the flattened portions of the shaft 77. The collars 82, 82 are held in place by means of a locking member 83 which abuts the outer ends of said collars and is secured to the rod 81 by means of suitable pins 84 so that pivotal movement of said rod will pivotally move said locking member about the axis thereof and longitudinal movement of said rod will pivotally move the lever arm 75. The locking member 83 is provided with forward and rearward beveled engaging surfaces 85, one of which surfaces is adapted to engage the forward engaging surface of a stop 86 and the other of which engaging surface is adapted to engage the rearward engaging surface of said stop to hold the rod 81 from longitudinal movement in one direction or another.

Collars 87, 87, having inwardly extending tongues, are likewise disposed adjacent opposite ends of the bifurcated portion of the parallel arm 79 and the tongues of said collars extend within said bifurcated portion and are adapted to abut the forward and rearward flattened surfaces of the shaft 80. A suitable collar 88 is secured to the rod 81 by means of a pin in an ordinary manner and abuts the forward surface of the forwardmost collar 87. The rearward collar 87 has a suitable recess formed therein which is adapted to receive an end of a tension member, such as a tension spring 89, encircling the rod 81 and enclosed by a sleeve member 90. The opposite end of the tension spring 89 passes through a suitable recess in the sleeve member 90 and is adapted to engage a suitable recess in a collar 91 secured to the rod 81 by means of a suitable pin 92 and abutting the rearward end of said sleeve member. The tension spring 89 is so arranged as to hold the locking member 83 in a vertical position for engagement with the stop 86 so the rod 81 must be turned against said tension spring when it is desired to disengage said lock-

ing member from said stop. The rod 81 is in turn turned to disengage the locking member 83 from the stop 86 and shifted longitudinally with respect to the machine by means of a handle 93 on the rearward end thereof.

Suitable stops 94, 94 are provided on the frame member 41 to engage the lever arm 75 at the extreme ends of its forward and rearward movement and react against the engaging surfaces 85 of the locking member 83 and stop 86 to positively hold the feed drum 15 from movement when locked in an engaged or disengaged position with respect to the shaft 46 when exceptional loads are placed on said feed drum.

It may thus be seen that when the rearward 15 engaging surface 85 of the locking member 83 is in engagement with the forward engaging surface of the stop 86, that the internal gear 48 is meshed with the pinion 47 so the feed drum 15 may be driven from the shaft 46 and rotated 20 about the center of the sleeve member 66 at either a high or low frictionally controlled speed. When the rearward engaging surface 85 is disengaged from the stop 86 and the rod 81 is moved rearwardly with respect to the machine, and the 25 forward engaging surface 85 is engaged with the rearward engaging surface of the stop 86, the feed drum 15 and internal gear 48 is moved rearwardly with respect to the machine a distance 30 sufficient to throw the pinion 47 out of mesh with said internal gear and hold said internal gear in such a position by means of the locking member 83 and stop 86.

It is thus apparent that a simplified and positive means has been provided for selectively connecting either of the feed drums 15 with the transversely extending shaft 46 so that either of said drums may be independently driven therefrom at either a high or low frictionally controlled speed in a simplified manner which utilizes a minimum amount of space in the machine proper, thus eliminating the use of the clutches for selectively connecting said drums to said shaft.

Suitable means are provided for holding the feed drums 15, 15 from rotation when disengaged from the transversely extending shaft 46, for retarding travel of one side or the other of the machine, or for holding said machine adjacent the face when cutting along a pitching face, which means may be of any ordinary type but are hereinafter shown as being friction brake bands 95, 95 engageable with the outer peripheries of the inwardly extending flanges 49 of said feed drums. The friction brake bands 95 are engaged with or disengaged from the inwardly extending flanges 49 by means of a suitable system of levers in an ordinary manner (not shown).

Safety means are further provided to prevent rotation of the feed drums 15, 15 in a direction opposite to which they are being driven from the motor 11 and thus to hold the machine while cutting along a pitching seam in cases where there might be breakage of the parts driving said feed drums, or in cases where said drums might accidentally be disconnected from the transversely extending shaft 46 so as to be free to rotate about their axes of pivotal connection to the frame member 41, which means may be of any type but which are herein preferably shown as being pawl and ratchet devices, generally indicated by reference character 96. The pawl and ratchet devices 96 are of the reversible type so as to be operative in whichever direction the feed drums 15, 15 are rotating and each of said pawl and ratchet devices includes ratchet teeth 97 cut in-

tegral with the inner end of the inwardly extending flanges 49 of each feed drum 15. A member 98 has a pair of pawls 99, 99 formed integral therewith, each of said pawls being at opposite ends 5 of said member. The member 98 is pivotally connected to a portion of the frame member 41 intermediate the pawls 99 and has an outwardly extending arcuate shaped engaging member 100 secured thereto, the concave face of which is 10 adapted to be engaged by a spring pressed plunger 101 pivotally connected to the frame member 41 in such a manner that said plunger may engage either end of the concave face of said engaging member and engage either of the pawls 99 with 15 the ratchet teeth 97 in an obvious manner.

It is thus apparent that the pawl and ratchet devices 96 may be adjusted to hold the feed drums 15 from rotation in any desired direction. Thus 20 when the machine is being fed along a pitching coal face and the feed drum 15 feeding the machine is disconnected from the motor 11, said drum will hold the machine from movement along the pitching bottom without engaging the brake band 95 therewith.

Referring now in particular to the means for 25 pivotally moving the cutter bar 13 about the axis of the vertical shaft 34 for feeding said cutter bar into the coal face or for positioning said cutter bar in its various positions of adjustment with 30 respect to the mining machine 10, suitable means driven by the frictionally controlled plural speed planetary gear reduction device 50 independently of the feed drums 15 are provided for so pivoting said cutter bar which include longitudinally 35 extending guide frames 103, 103 disposed on each side of the frame member 41. Each longitudinally extending guide frame 103 is secured adjacent its forward end to the outer side of the forward portion of the frame member 41 and 40 adjacent the rearward end of the motor 11 by means of a suitable bracket 104 pivotally supported on the outer side of the frame member 41 for pivotal movement about an axis spaced downwardly from said guide frame. Each guide 45 frame 103 is supported adjacent its rearward end on a pin 105 secured to the end of a lever arm 106, which lever arm in turn is secured to a transversely extending shaft 107 disposed rearwardly of said guide frame.

50 A rack 109 is slidably mounted in each longitudinally extending guide frame 103 for longitudinal movement with respect thereto, and is held from vertical movement with respect to its 55 associated guide frame by means of a gibbed member 108 engaging a shouldered portion on said rack. Pinions 110, 110 are keyed on the outer ends of shafts 111, 111 journaled adjacent opposite sides of the frame member 41. The pinions 110, 110 are adapted to mesh with the 60 racks 109, 109 for translationally moving said racks upon rotation thereof. Spur gears 112, 112 are keyed on the opposite end of the shafts 111, 111 and are meshed with and driven by the pinions 47, 47 on opposite ends of the transversely 65 extending shaft 46.

Suitable operating levers 113, 113 are secured 70 to the transversely extending shafts 107, 107 for pivotally moving said shafts and moving the guide frames 103, 103 about their axes of pivotal connection to the frame member 41, and raising or depressing the rearward ends of the racks 109, 109 for engaging the teeth of said racks with the pinions 110, 110 or disengaging said racks therefrom. The operating levers 113, 113 are provided 75 with suitable spring pressed pins 114, 114 adapted

to register with suitable apertures in members 115, 115 integral with the frame member 41 for holding the racks 109, 109 in an engaged or disengaged position with respect to the pinions 110, 110 in such a manner that said racks may be retracted or extended independently of each other and independently of the feed drums 15, 15. 5

Upwardly extending apertured connecting members 116, 116 are provided on the forward ends of the racks 109, 109 and the apertures in 10 either one of said members are adapted to be engaged by a hook 117 on the rearward end of a flexible cable 118 (see Figs. 1, 4, and 5). The opposite end of the flexible cable 118 is provided with a suitable hook 119 which is adapted to 15 engage a suitable recessed portion 120 formed in the outer periphery of the cutter bar support member 17 for pivotally moving said cutter bar support member upon longitudinal movement of the respective rack 109 to which the cable 118 is 20 connected (see Figs. 1 and 2).

It is thus apparent that when the flexible cable 118 is connected adjacent one of its ends to the recessed portion 120 and adjacent its opposite end to the connecting member 116 secured to the 25 rack 109, that movement of said rack will pivotally move the cutter bar 13 in an obvious manner. It should also be apparent that when pivotally moving the cutter bar 13 in one direction, one rack 109 is utilized and when moving 30 said cutter bar in an opposite direction the opposite rack 109 is utilized.

It should be understood that the racks 109, 109 are moved rearwardly with respect to the mining machine 10 when it is desired that either 35 of said racks effect pivotal movement of the cutter bar 13. When it is desired to extend either of the racks 109, 109 to an operative position after they have been moved in a rearward position, it is only necessary to reverse the direction of rotation of the motor 11, although it should be apparent that suitable reversing mechanism may be provided to reverse the direction of movement of said racks without reversal of 40 said motor if desired. 45

It may now be seen that a new and improved means has been provided for pivotally moving the cutter bar 13, which means is selectively connectible with and driven from the mining machine motor 11 at either a high or low frictionally controlled speed independently of the feed drums 50 15, 15.

With such an arrangement, the cutter bar 13 may be pivoted about the axis of the vertical shaft 34 at either a high or low frictionally controlled speed while the mining machine is being held to the face by both of the flexible cables 118 wound on the feed drums 15. Thus the cutter bar 13 may be positioned for cutting or sumped into the coal independently of the feed 60 drums 15 while said machine is held from movement along the mine bottom by said feed drums, which means is entirely independent of said feed drums and permits the mining machine to be safely and efficiently operated where the bottom 65 and coal seam is pitching.

While I have herein shown and described one form in which my invention may be embodied, it will be understood that the construction and arrangement of the various parts may be altered 70 or changed without departing from the spirit and scope thereof. Furthermore, I do not wish to be construed as limiting myself to the particular form illustrated, excepting as it may be limited in the appended claims. 75

I claim as my invention:

1. In a mining machine, a motor, a cutter bar projecting forwardly of said motor and carried for pivotal movement about a vertical axis, feeding mechanism for said mining machine comprising a feed drum, a drive connection from said motor to said feed drum including a transverse shaft driven by said motor and having a pinion thereon, and means driven by said pinion and operable independently of said feed drum for pivoting said cutter bar about a vertical axis comprising a rack, a pinion meshing with said rack, and a connection from said rack to said cutter bar. 10
15. 2. In a mining machine, a motor, a cutter bar projecting forwardly of said motor and carried for pivotal movement about a vertical axis, feeding mechanism for said mining machine comprising a feed drum, a drive connection from said motor to said feed drum including a transverse shaft driven by said motor and having a pinion thereon, and means driven by said pinion and operable independently of said feed drum for pivoting said cutter bar about a vertical axis comprising a rack, 20 a pinion meshing with said rack, and a connection from said rack to said cutter bar. 25
3. In a mining machine, a frame, a motor, a projecting cutter bar extending forwardly of said motor and carried for pivotal movement about a vertical axis, feeding mechanism on said frame comprising a feed drum on each side thereof, a drive connection from said motor to said feed drums including a frictionally controlled plural speed gear reduction device, and means driven 30 by said frictionally controlled plural speed gear reduction device for pivoting said cutter bar about a vertical axis comprising a rack, a pinion meshing with said rack and driven by said frictionally controlled plural speed gear reduction 35 device, and a connection from said rack to said cutter bar for pivotally moving said cutter bar upon movement of said rack. 40
4. In a mining machine, a frame, a motor, a projecting cutter bar extending forwardly of said motor and carried for pivotal movement about a vertical axis, feeding mechanism on said frame comprising a feed drum on each side thereof, a drive connection from said motor to said feed drums including a frictionally controlled plural speed gear reduction device, and means driven 45 by said frictionally controlled plural speed gear reduction device for pivoting said cutter bar about a vertical axis comprising a rack, a pinion meshing with said rack and driven by said frictionally controlled plural speed gear reduction 50 device, and a flexible connection from said rack to said cutter bar for pivotally moving said cutter bar upon movement of said rack. 55
5. In a mining machine, a frame, a motor, a projecting cutter bar extending forwardly of said motor and carried for pivotal movement about a vertical axis, feeding mechanism on said frame comprising a feed drum on each side thereof, a drive connection from said motor to said feed drums including a frictionally controlled plural speed gear reduction device, and means driven 60 by said frictionally controlled plural speed gear reduction device for pivoting said cutter bar about a vertical axis comprising a rack extending along and on each side of said frame, pinions meshing with said racks and driven by said frictionally controlled plural speed gear reduction device, and connections from said racks to said cutter bar whereby either of said racks may 65 pivotally move said cutter bar. 70
6. In a mining machine, a frame, a motor, a projecting cutter bar extending forwardly of said motor and carried for pivotal movement about a vertical axis, feeding mechanism on said frame comprising a feed drum on each side thereof, a drive connection from said motor to said feed drums including a frictionally controlled plural speed gear reduction device, and means driven 75 by said frictionally controlled plural speed gear reduction device for pivoting said cutter bar about a vertical axis comprising a rack extending along and on each side of said frame, pinions meshing with said racks and driven by said frictionally controlled plural speed gear reduction device, and a flexible connecting member adapted to connect either of said racks to said cutter bar. 80
7. In a mining machine, a motor, cutting mechanism disposed forwardly of said motor including a horizontal plane chain carrying cutter bar pivotally movable about a vertical axis, feeding mechanism disposed rearwardly of said motor including a feed drum and a transversely extending shaft operably connected with said feed drum adjacent its outer end selectively driven by said motor, and other means driven from said shaft independently of said feed drum for pivotally moving said cutter bar about a vertical axis comprising a rack adapted to have connection with said cutter bar, a pinion meshing 85 therewith, and a drive connection from said shaft to said pinion. 90
8. In a mining machine, a motor, cutting mechanism disposed forwardly of said motor including a horizontal plane chain carrying cutter bar pivotally movable about a vertical axis, feeding mechanism disposed rearwardly of said motor including a plurality of feed drums arranged at opposite sides of said machine, a shaft extending transversely thereof and independently driven by said motor, a selective drive connection from opposite ends of said shaft to said feed drums and other means driven from said shaft independently of said feed drums for pivoting said cutter bar about a vertical axis comprising a rack 95 arranged on each side of said mining machine, each of said racks being adapted to have selective connection with said cutter bar, a pinion meshing with each of said racks, and drive connections from said shaft to said pinions. 100
9. In a mining machine, a motor, cutting mechanism disposed forwardly of said motor including a chain carrying cutter bar pivotally movable about a vertical axis, feeding mechanism disposed rearwardly of said motor including a plurality of feed drums arranged at opposite sides of said machine for rotation about axes extending transversely of said mining machine, means for driving said feed drums from said motor independently of each other including a shaft extending transversely of said mining machine, and means driven by said shaft for pivoting said cutter bar about a vertical axis comprising a retractable member arranged on each side of said mining machine, each of said retractable members being adapted 105 to have selective connection with said cutter bar, and drive connections from said transversely extending shaft to said retractable members including inter-engaging rotating members cooperating with said retractable members. 110
10. In a mining machine, a motor, cutting mechanism disposed forwardly of said motor including a chain carrying cutter bar pivotally movable about a vertical axis, feeding mechanism disposed rearwardly of said motor including a plu- 115

- rality of feed drums arranged at opposite sides of said machine for rotation about axes extending transversely of said mining machine, means for driving said feed drums from said motor independently of each other including a plural speed gear reduction device, a shaft extending transversely of said mining machine driven by said plural speed gear reduction device and having selective connection with said feed drums, and means driven by said shaft independently of said feed drums for pivoting said cutter bar about a vertical axis comprising a retractable member arranged on each side of said mining machine, each of said retractable members being adapted to have selective connection with said cutter bar, and drive connections from said transversely extending shaft to said retractable members including inter-engaging rotating members cooperating with said retractable members.
11. In a mining machine, a motor, cutting mechanism disposed forwardly of said motor including a chain carrying cutter bar pivotally movable about a vertical axis, feeding mechanism disposed rearwardly of said motor including a plurality of feed drums arranged at opposite sides of said machine for rotation about axes extending transversely of said mining machine, means for driving said feed drums from said motor independently of each other including a shaft extending transversely of said mining machine, and means driven by said shaft for pivoting said cutter bar about a vertical axis comprising an extensible and retractable member arranged on each side of said mining machine, each of said extensible and retractable members being adapted to have selective connection with said cutter bar, and drive connections from said transversely extending shaft to said extensible and retractable members including inter-engaging rotating members cooperating with said retractable members.
12. In a mining machine, a motor, cutting mechanism disposed forwardly of said motor including a chain carrying cutter bar pivotally movable about a vertical axis, feeding mechanism disposed rearwardly of said motor including a plurality of feed drums arranged at opposite sides of said machine for rotation about axes extending transversely of said mining machine, means for driving said feed drums from said motor independently of each other including a plural speed gear reduction device, a shaft extending transversely of said mining machine driven thereby and having selective connection with said feed drums, and means driven by said shaft independently of said feed drums for pivoting said cutter bar about a vertical axis comprising an extensible and retractable member arranged on each side of said mining machine, each of said extensible and retractable members being adapted to have selective connection with said cutter bar, and selective drive connections from said transversely extending shaft to said extensible and retractable members including inter-engaging rotating members cooperating with said retractable members.
13. In a longwall mining machine, a motor, a cutter bar projecting forwardly of said motor and carried for pivotal movement about a vertical axis, and means driven by said motor for pivotally moving said cutter bar comprising a rack connectible with said cutter bar and movable longitudinally of said machine in a plane parallel to the plane of said cutter bar, a pinion driven by said motor and adapted to mesh with said

rack and a selective connection between said pinion and rack.

14. In a longwall mining machine, a motor, a cutter bar projecting forwardly of said motor and carried for pivotal movement about a vertical axis, means driven by said motor for pivoting said cutter bar comprising a rack on each side of said machine, said racks being independently movable in a plane parallel to the plane of said cutter bar and adapted to have detachable connection with said cutter bar, and a selective drive connection from said motor to said racks including a frictionally controlled gear reduction device, a pair of pinions driven thereby and selective connections between said pinions and racks.

15. In a longwall mining machine, a motor, a cutter bar projecting forwardly of said motor and carried for pivotal movement about a vertical axis, and feeding mechanism therefor including a plurality of feed drums rotatable about transverse axes and disposed at opposite sides of said machine, means for independently driving said feed drums from said motor including a frictionally controlled plural speed gear reduction device, a transversely extending shaft coaxial with and driven by said plural speed gear reduction device, and a selective connection from said shaft to said feed drums, braking mechanism associated with each of said feed drums, and means automatically operable independently of said braking mechanism for holding said feed drums from rotation in a direction opposite to the direction in which they are being driven comprising a pawl and ratchet device engageable with each of said drums.

16. In a longwall mining machine, a motor, a cutting section carried forwardly of said motor including a projecting chain carrying cutter bar carried for pivotal movement about a vertical axis and a feeding section rearwardly of said motor including a plurality of feed drums rotatable about transverse axes and disposed at opposite sides of said feeding section, means for independently driving said feed drums from said motor including a frictionally controlled plural speed gear reduction device, a transversely extending shaft coaxial with and driven by said plural speed gear reduction device, means for selectively connecting opposite ends of said shaft with said feed drums, braking mechanism associated with each of said feed drums, and means operable upon disengagement of said braking mechanism from said feed drums for holding said feed drums from rotation in a direction opposite to the direction in which they are being driven comprising a pawl and ratchet device engageable with each of said drums.

17. In a longwall machine, a motor, a cutter bar projecting forwardly of said motor and carried for pivotal movement about a vertical axis, and feeding mechanism therefor including a plurality of feed drums rotatable about transverse axes and disposed at opposite sides of said feeding section, means for independently driving said feed drums from said motor including a frictionally controlled plural speed gear reduction device, a transversely extending shaft coaxial with and driven by said plural speed gear reduction device, means for selectively connecting opposite ends of said shaft with said feed drums, braking mechanism associated with each of said feed drums, and means automatically operable independently of said braking mechanism for holding said feed drums from rotation in a direction opposite to the direction in which they are being

- driven comprising a pawl and ratchet device engageable with each of said drums and other means driven from said transversely extending shaft for turning said cutter bar comprising extensible and retractable members on each side of said mining machine, and a flexible connecting member for connecting either of said extensible and retractable members with said cutter bar.
18. In a longwall mining machine, a motor, a cutter bar for projecting forwardly of said motor and carried for pivotal movement about a vertical axis, and feeding mechanism therefor including a plurality of feed drums rotatable about transverse axes and disposed at opposite sides of said machine, braking mechanism associated with each of said feed drums, means automatically operable independently of said braking mechanism for holding said drums from rotation in a direction opposite to the direction in which they are being driven comprising a pawl and ratchet device associated with each of said drums and means for independently driving said feed drums from said motor at either a high or low frictionally controlled speed including a frictionally controlled plural speed planetary gear reduction device, a transversely extending shaft coaxial with and driven by said plural speed gear reduction device, pinions on opposite ends of said shaft, gears on said feed drums, and eccentric devices for independently meshing said gears with said pinions or disengaging said gears therefrom.
19. In a mining machine, a motor, a cutter bar disposed forwardly of said motor, feeding mechanism therefor including a feed drum, means for driving said feed drum from said motor including a shaft, a pinion on said shaft, a gear on said feed drum driven by said pinion and means for meshing said gear on said feed drum with said pinion or disengaging said gear therefrom comprising a sleeve member journaled within said drum and supporting said drum for rotation with respect thereto, said sleeve member being supported for pivotal movement about an axis disposed eccentrically of its center, and means for pivoting said sleeve member and shifting said gear for engagement with or disengagement from said pinion comprising a lever arm having connection with said sleeve member, a parallel arm, means for connecting said arms together so that horizontal movement of said connecting means will cause pivotal movement of said arms comprising a horizontally extending rod, and means carried by said rod for selectively locking said arms in one extreme position or another and positively locking said gear in an engaged or disengaged position with respect to said pinion.
20. In a mining machine, a motor, a cutter bar disposed forwardly of said motor, feeding mechanism therefor including a feed drum, means for driving said feed drum from said motor including a shaft, a pinion on said shaft, a gear on said feed drum driven by said pinion and means for meshing said gear on said feed drum with said pinion or disengaging said gear therefrom comprising a sleeve member journaled within said drum and supporting said drum for rotation with respect thereto, said sleeve member being supported for pivotal movement about an axis disposed eccentrically of its center, and means for pivoting said sleeve member and shifting said gear for engagement with or disengagement from said pinion comprising a lever arm having connection with said sleeve member, a parallel arm, means for connecting said arms together so that horizontal movement of said connecting means will cause pivotal movement of said arms comprising a horizontally extending rod, and means carried by said rod for selectively locking said arms in one extreme position or another and positively locking said gear in an engaged or disengaged position with respect to said pinion.
21. In a mining machine, a motor, cutting mechanism disposed forwardly of said motor including a chain carrying cutter bar pivotally movable about a vertical axis, feeding mechanism disposed rearwardly of said motor including a plurality of feed drums arranged at opposite sides of said machine for rotation about axes extending transversely of said mining machine, means for driving said feed drums from said motor independently of each other including a shaft extending transversely of said mining machine, and means driven by said shaft for pivoting said cutter bar about a vertical axis comprising a longitudinal guide on each side of said mining machine, a retractable member selectively driven by said motor slidably movable in said guide, and a connection from said retractable member to said cutter bar.
22. In a mining machine, a motor, cutting mechanism disposed forwardly of said motor including a chain carrying cutter bar pivotally movable about a vertical axis, feeding mechanism disposed rearwardly of said motor including a plurality of feed drums arranged at opposite sides of said machine for rotation about axes extending transversely of said mining machine, means for driving said feed drums from said motor independently of each other including a shaft extending transversely of said mining machine, and means driven by said shaft for pivoting said cutter bar about a vertical axis comprising a longitudinal guide on each side of said mining machine, a retractable member slidably movable on said guide, said retractable members being adapted to be connected to said cutter bar, and selective drive connections from said transversely extending shaft to said retractable members.
23. In a mining machine, a motor, cutting mechanism disposed forwardly of said motor including a chain carrying cutter bar pivotally movable about a vertical axis, feeding mechanism disposed rearwardly of said motor including a plurality of feed drums arranged at opposite sides of said machine for rotation about axes extending transversely of said mining machine, means for driving said feed drums from said motor independently of each other including a shaft extending transversely of said mining machine, and means driven by said shaft for pivoting said cutter bar about a vertical axis comprising a longitudinal guide on each side of said mining machine, a retractable member slidably movable on said guide, said retractable members being adapted to be connected to said cutter bar, and selective drive connections from said transversely extending shaft to said retractable members including interengaging rotating members driven by said shaft and cooperating with said retractable members.
24. In a mining machine, a motor, cutting mechanism disposed forwardly of said motor including a chain carrying cutter bar pivotally movable about a vertical axis, feeding mecha-

- nism disposed rearwardly of said motor including a plurality of feed drums arranged at opposite sides of said machine for rotation about axes extending transversely of said mining machine, means for driving said feed drums from said motor independently of each other including a shaft extending transversely of said mining machine, and means driven by said shaft for pivoting said cutter bar about a vertical axis comprising a longitudinal guide on each side of said mining machine, a retractable member slidably movable on said guide, said retractable members being adapted to be connected to said cutter bar, and selective drive connections from said transversely extending shaft to said retractable members comprising interengaging rotating members driven by said shaft and means for selectively engaging said retractable members with said interengaging rotating members.
25. In a mining machine, a motor, cutting mechanism disposed forwardly of said motor including a chain carrying cutter bar pivotally movable about a vertical axis, feeding mecha-
- nism disposed rearwardly of said motor including a plurality of feed drums arranged at opposite sides of said machine for rotation about axes extending transversely of said mining machine, means for driving said feed drums from said motor independently of each other including a shaft extending transversely of said mining machine, and means driven by said shaft for pivoting said cutter bar about a vertical axis comprising a longitudinal guide on each side of said mining machine, a retractable member slidably movable on said guide, said retractable members being adapted to be connected to said cutter bar, and selective drive connections from said transversely extending shaft to said retractable members comprising interengaging rotating members driven by said shaft and means for selectively engaging said retractable members with said interengaging rotating members comprising means for swinging said guide members in a vertical plane. 5 10 15 20
